AMUSEMENT GAME APPARATUS

Bruno Radtke, Chicago, Ill., assignor to John F. Meyer, Chicago, Ill.

Original application August 24, 1934, Serial No. 741,203. Divided and this application August 24, 1934, Serial No. 741,204

7 Claims. (Cl. 273—121)

My invention relates to certain novel improvements in amusement game apparatus, and has for its principal object the provision of an improved construction of this character which will be economical in manufacture and afford the greatest amount of amusement.

The present application is a division of my co-pending application Serial No. 741,203, filed August 24, 1934 upon a Game apparatus.

10 Among the several objects of this invention is to embody in a game apparatus an arrangement for propelling a ball or a plurality of balls upwardly upon an inclined play board for passage into and through score bearing exit openings by 15 means of mechanism controlled in its operation by a projected ball passing through another exit opening provided by the play board, all to the amusement of and by the skill of the operator.

A still further object of the invention is the 20 provision of a play board having an area, passage upon which is obstructed in a manner such that one or more balls are first collected in a runway and then subsequently permitted to gravitate therefrom, after being released for such gravitation, by means of mechanism operated by another ball passing through one of several exit openings formed in the play board, the balls thus released from said runway being permitted 25 to gravitate to a position against a ball stop of a re-projection device which when operated is adapted to re-project the balls back upon said area of the play board into and through score bearing ball exit openings formed in the play board within said area.

30 Other objects will appear hereinafter.

The invention consists in the novel combination and arrangement of parts to be hereinafter described and claimed.

35 The invention will be best understood by reference to the accompanying drawings, showing the preferred form of construction and in which:

Fig. 1 is a plan view of an amusement game apparatus embodying the invention;

40 Fig. 2 is a fragmentary sectional detail view of the same taken substantially on line 2—2 of Fig. 1;

Fig. 3 is a fragmentary perspective view of the invention illustrating the ball retaining means 45 and ball re-projecting means embodied in the invention;

Fig. 4 is a fragmentary sectional detail view of the invention taken substantially on line 4—4 of Fig. 1;

50 Fig. 5 is a fragmentary sectional detail view of

the invention taken substantially on line 5—5 of Fig. 1;

Fig. 6 is a bottom plan view of the invention taken substantially on line 6—6 of Fig. 2; and

Fig. 7 is a diagrammatical plan view of an 5 electric circuit embodied in the invention.

Referring now more particularly to the drawings illustrating the preferred form of construction of my invention, a cabinet is indicated at 10 and includes a glass top (not shown) beneath 10 which is arranged a play board 11.

This play board 11 has formed therein a plurality of ball exit openings 12, all or many of which may be indicated by a numerical score.

At one side of the play board 11 is a ramp 13 through which balls 14 are projected by a projecting or propelling device 15 upon the play board 11 which is inclined to permit the balls thus propelled thereupon to gravitate toward the lower end thereof, the balls being elevated into 20 projecting position with respect to the propelling device 15 by means of any suitable elevating mechanism (not shown) including an operating plunger 16.

Slidably supported beneath the play board 11 in any suitable manner, such as, for example, by means of brackets 17, is a gate 18 having formed therein openings 19 adapted to register under certain conditions with the ball exit openings 12, the said gate being operated simultaneously with the operation of a coin slide 20 of a coin device 21 in a well known manner, to bring the openings 19 into registration with the exit openings 12 to permit the balls to pass through the openings 19 upon a floor 21 where the balls are gravitated to a position to be elevated by the elevating means 16 to the propelling device 15.

The description of the construction of the amusement game apparatus thus far set forth is well known in the art of amusement game apparatus.

My invention, as previously pointed out, particularly relates to a novel and efficient means for re-projecting balls upon an area of the play board where the balls are again permitted to gravitate to a position for passage into and through ball exit openings. The invention also contemplates means to collect the balls within a runway where the balls are thus held until released, for movement to the re-projection mechanism; by mechanism operated by the action of another ball passing through one of several of the exit openings 12.

In this connection, while I have shown the 55

play board 11 defining an area within which the balls are to be re-projected, it is to be understood that the ball re-projecting means may be utilized in connection with the play board without having any specific area defined over which these balls are adapted to be re-projected for re-gravitation down upon the board.

To accomplish the several objects of the invention, this area is defined by rail members 22, sections of which are brought into parallel relationship with respect to each other as at 23 to provide a runway 24 having a funnel shaped entrance 24'. In this runway 24 there is formed an opening 25.

Normally closing this opening is a trap door 26 hinged to the play board as at 27. This trap door is normally moved into ball releasing position by movement of the gate 18. This gate 18 is connected to a depending arm 28 of the trap door by means of a rod 29 so that, when the gate 18 is moved by action of the coin slide 20 in a well known manner, the trap door 26 will simultaneously pivot therewith into ball releasing or discharging position.

Preferably, though not necessarily, the return movement of the gate 18 and trap door 26 is governed by an air pump 30 having connection with the arm 28 through the medium of the link elements 31, the said pump being substantially similar to that shown and described in my pending application, Serial No. 715,573, filed in the United States Patent Office, on or about the 14th day of March, 1934.

To releasably hold balls in the runway 24, I provide a ball stop arm 32 pivotally supported upon a pivot pin 33 for movement in a horizontal plane, the said pin 33 being supported by a suitable bracket 34 adapted to be secured to the under side of the play board 11 by means of an attaching element (not shown) projected through openings 35 formed in a wall of the bracket 34. The stop arm 32 is provided with a depending portion 36, Fig. 2, the lower end of which provides oppositely disposed arms 37 and 38, the arm 38 having one end of a spring 39 attached thereto, the other end of the spring being attached to a depending lug 40 provided by the bracket 31 whereby the spring will normally hold the arm in ball stopping position. When a number of balls have been collected in the runway 24 and the ball stop arm 32 is released for pivotal movement, in a manner hereinafter set forth, the downwardly inclined weight of the balls 14 will automatically pivot the arm in a direction to permit the balls 14 to pass upon the area of the play board 11 defined by the rail elements 22 into position against the ball re-projecting device hereinafter referred to.

The ball stop arm 32 is operatively controlled by electro-magnetic means which will now be described in detail:

An electro-magnetic solenoid is indicated at 41 and is connected in circuit with a suitable source of electric energy 42 by means of conductor wires 43.

The solenoid arm is indicated at 44 and this arm is disposed beneath the counterweighted end portion 45 of a latch arm 46 which is pivotally supported by the bracket 34 as at 47.

This latch arm 46 is provided with an enlarged head 48 having a two-stepped notch 49 formed therein with the bottom of one portion of the notch indicated at 50 disposed in a plane

beneath the other portion of the notch indicated at 51.

The arm 37 projects into the notch 49 as best shown in Fig. 3.

When the solenoid arm 44 is disposed in an ineffective position with respect to the latch arm 46, the counterweighted end portion 45 of the latch arm 46 will pivot the latter (clockwise, Fig. 2) into a position to dispose the arm 37 in the notch portion 49 and when this arm 37 is thus so disposed, it will engage the vertical edge 52 of the notch 49 and thereby releasably hold the ball stop arm 32 against pivotal movement by the action of the balls 14 in the runway 24.

When the electro-magnetic solenoid 41 is energized in a manner to be hereinafter set forth, the solenoid or armature 44 is lifted and engages and pivots the latch arm 46 (counterclockwise, Fig. 2), thereby causing the latch head 48 to engage the arm 37 and move the latter (left to right, Fig. 3) onto the notched portion 51 of the member 46-48, thereby permitting the balls in the runway 24 to gravitate therefrom into the area of the play board defined by the rails 22. After the balls have passed from the runway 24, the spring 39 will act to reset the stop arm 32 into ball stopping position. When thus reset, the portion 31 of the stop arm 32 will again be disposed in the notch portion 50 and by reason of the hook shaped head 48, the stop arm 32 will be held against pivotal movement by the action of any balls collected in the runway 24.

I have referred to the mechanism indicated at "R" as a ball re-projecting means so as to distinguish the same from the main ball propelling device 15 and for the further reason that this mechanism re-projects balls upon the play board after the balls have been projected thereupon by the propelling device and have found passage through the runway 24 and onto the area of the play board defined by the rails 22.

This mechanism "R" comprises a U-shaped plate 53 adapted to be secured to the under side of the play board, adjacent the edges of an elongated opening 55 formed in the play board 11, by means of attaching screws 54. This plate 53 is provided with oppositely disposed upstanding lugs 56 to which are pivotally supported the parallel arms 57 of a kick-bar 58. This kick-bar 58 includes a vertically extending wall 59 from the top edge 60 of which extends a hood 61 which is semi-circular in cross section.

One of the parallel arms 57, indicated at 62, provides a depending finger 63 adapted to be engaged by the head 64 of a hammer-arm 65.

This arm 65 is pivotally supported as at 66 by a bracket 67.

The end 68 of the arm 65 at one side of the pivotal connection 66 carries a plate 69 which is adapted to be attracted by the pole 70 of a magnetic coil 71 with such force as will be sufficient to bring the head 64 in hammer-action against the finger 63 so as to forcibly pivot the kick-bar 58 against balls resting thereagainst, so as to project these balls upwardly upon the inclined board either directly into the exit openings indicated at 72 or against pin elements 73 for possible deflection into these openings 72; the bar 58 being reset after this operation by its resetting spring 92.

The hammer-arm 65 is nicely balanced above its pivot 66 and in this balance it is assisted by action of a spring 74.

Forwardly of this mechanism "R" and mounted

in an extension 75 of the opening 55 is a ball release plate 76 which is pivotally supported by the play board as at 77 through the medium of parallel extending ears 78 and a pintle 79. This plate 76 is normally held in ball supporting position through the medium of a spring 80 and is adapted to support the balls in front of the bar 58.

Movement of the plate 76 into ball releasing position is controlled by the gate 18 and this is accomplished by mounting upon the gate 18 a forwardly extending finger 81, the outer end of which engages an adjacent portion 82 of the plate 76 and thereby acts to hold this plate 76 in ball supporting position when the gate 18 is in a position to support the balls 14 in the exit openings 12.

The magnetic coil 71 is disposed in the circuit provided by the conductor wires 43. The electric energy to this magnetic coil as well as to the solenoid 41 is controlled by means of a ball actuated switch indicated at "S", the construction of which will now be explained:

This switch includes spaced contact arms 83 adapted to be momentarily contacted by means 25 of a connector bar 84 supported by the enlarged tail 85 of the switch arm 86 which arm is pivotally supported by a pin 87 carried by side walls 88 of a ball trough 89. The ball trough 89 is disposed beneath one of the exit openings indicated at 90 and which I prefer to term the master exit opening. The arrangement is such that a ball passing through this master exit opening 90 will drop upon the arm 86, pivot the same in a direction to bring the bar 84 against the contact 35 arms 83, thereby to complete an electric circuit between the source of electric energy 42 and the magnetic coil 71 and solenoid 41.

Pins or other baffles indicated at 91 may be disposed in pre-determined positions upon the 40 play board to increase the necessary skill of the game.

The amusement game apparatus is played as follows:

A coin is inserted in the slide 20 and when this 45 slide 20 is moved inwardly the gate 18 is moved into ball releasing position and simultaneously therewith, the trap 26 and the plate 76 move into ball releasing position so that if any balls are positioned upon the trap 26 and plate 76 or within 50 the exit openings 12, they will be released for movement to a position to be successively elevated into position to be projected by the propelling device 17 upon the play board, whereupon these balls as successively projected upon the 55 play board may find entrance into the runway 24 where they will collect against the arm 32.

Should the next ball find passage through the master exit opening 90 the same will operate the switch structure "S" and thereby complete 60 a circuit between the source of electric energy 42 and the solenoid 41. Upon operation of the solenoid 41, the weight of the balls 14 will pivot the arm 32 after the same has been released for this pivotal movement in a manner hereinbefore set forth.

Upon release of these balls they will pass within the area provided by the rails 22 and gravitate into a position to be re-projected upon the area thus defined by these rails 22 by the projecting 70 means "R" hereinbefore described. Should the next ball projected by the propelling means 15 upon the play board 11 find entrance through the master exit opening 90 this ball will operate, as stated before, the switch "S" and complete an electric circuit between the source of electric 75

energy 42 and the magnetic coil 71, whereupon the magnetic coil 71 thus energized will operate the hammer 65 in hammer-like action, striking the kick-bar 58 against the balls collected thereagainst and project these balls back upon the area within the rails 22 to find lodgment in the exit openings 12 or again return into engagement with the kick-bar 58, as the case may be.

This operation is continued until the allotted 10 number of balls has been propelled upon the play board, which allotted number of balls may vary according to the usage or construction of the game.

While I have illustrated and described the preferred form of construction for carrying my invention into effect, this is capable of variation and modification, without departing from the spirit of the invention. I, therefore, do not wish to be limited to the precise details of construction set forth, but desire to avail myself of such variations 15 and modifications as come within the scope of the appended claims.

Having thus described my invention, what I 20 claim as new and desire to protect by Letters Patent is:

1. A ball retaining device comprising a supporting bracket, a ball-obstructing arm pivotally supported by said bracket for movement through a horizontal plane and having a portion thereof providing a latch finger, and a latch member pivotally supported by said bracket and having a head provided with a two-stepped notch for the reception of said latch finger.

2. A ball retaining device for a game apparatus in which there is provided a play board having a ball exit opening or pocket formed therein and said board having a runway upon its surface through which balls are adapted to pass, comprising a stop arm pivotally supported by the board for horizontal movement into and from ball-obstructing position in said runway, latch means for said arm including a head cooperating with the arm and with the weight of one or more balls disposed against said arm to hold said arm in ball-obstructing position, and means actuated by a ball 40 entering said ball exit opening or pocket for actuating said latch means to release said arm for movement from said ball-obstructing position by movement of the balls through said runway.

3. A ball retaining device for a game apparatus in which there is provided a play board having a ball exit opening formed therein and said board having a runway upon its surface through which balls are adapted to pass, comprising a stop arm pivotally supported by the board for horizontal movement into and from ball-obstructing position in said runway, latch means for said arm including a head cooperating with the arm and with the weight of one or more balls disposed against said arm to hold said arm in ball-obstructing position, and means including an electromagnetic device actuated by a ball passing through said exit opening for actuating said latch means to release said arm for movement from said ball-obstructing position by movement of the balls through said runway.

4. A ball retaining device for a game apparatus in which there is provided a play board having a ball exit opening formed therein and having a runway upon its surface through which balls are 70 adapted to pass, comprising a stop arm pivotally supported by the board for horizontal movement into and from ball-obstructing position in said runway, latch means for said arm including a head cooperating with the arm and with the 75

weight of one or more balls disposed against said arm to hold said arm in ball-obstructing position, and means actuated by a ball passing through said exit opening for actuating said latch means to release said arm for movement from said ball-obstructing position by movement of the balls through said runway, said head having means cooperating with said arm when the weight of the said balls is disposed against said arm to hold 10 said latch means from latched position with respect to said arm until all of the said balls have passed through said runway.

5. A ball retaining device for a game apparatus in which there is provided a play board having a 15 ball exit opening formed therein and having a runway upon its surface through which balls are adapted to pass, comprising a stop arm pivotally supported by the board for horizontal movement into and from ball-obstructing position in said 20 runway, latch means for said arm including a head cooperating with the arm and with the weight of one or more balls disposed against said arm to hold said arm in ball-obstructing position, and means actuated by a ball passing through said 25 exit opening for actuating said latch means to release said arm for movement from said ball-obstructing position by movement of the balls through said runway, said head having means cooperating with said arm when the weight of the 30 said balls is disposed against said arm to hold

said latch means from latched position with respect to said arm until all of the said balls have passed through said runway.

6. A ball retaining device comprising a supporting bracket, a ball-obstructing arm pivotally supported by said bracket for movement through a horizontal plane and having a portion thereof providing a latch finger, a latch member pivotally supported by said bracket and having a head provided with a two-stepped notch for the reception 10 of said latch finger, and magnetic means for operating said latch member.

7. An amusement game apparatus comprising an inclined board having an opening formed therein and upon which balls are adapted to be 15 projected for gravitation thereupon, means for projecting said balls upon said board, a trap door pivotally supported in said opening, means providing with said trap door a runway, an arm pivotally supported by said board for horizontal 20 movement into and from ball-obstructing position in said runway and adapted, when in ball-obstructing position, to obstruct the balls upon said trap door, latch means for said arm for latching said arm in said ball-obstructing position, and 25 magnetic means for actuating said latch means to permit movement of said arm from ball-obstructing position by the weight of the balls against said arm.

BRUNO RADTKE. 30
